UNITED STATES PATENT OFFICE.

ELMER A. BARTON, OF PHILADELPHIA, PENNSYLVANIA, ASSIGNOR OF ONE-HALF TO
HUGH W. JUBY, OF PHILADELPHIA, PENNSYLVANIA.

PICKER CONNECTION FOR LOOMS.

Application filed December 12, 1924. Serial No. 755,492.

To all whom it may concern:

Be it known that I, ELMER A. BARTON, a citizen of the United States, residing in Philadelphia, Pennsylvania, have invented 5 certain Improvements in Picker Connections for Looms, of which the following is a specification.

Prior to my present invention various devices have been invented for supporting and 10 operatively connecting the sweep stick and lug strap to the picker stick of a loom. Such prior art devices have not been entirely satisfactory, the proof being that the great majority of looms are still equipped 15 with the old type of support for the lug strap which consists of a loop of leather secured to the outer edge surface of the picker stick and which extends through the outer end of the lug strap. Practically every 20 weaver knows the disadvantages of said old type of connection since it gives constant trouble and in no way protects the picker stick against breaking due to the severe action required in throwing the shuttle across 25 the race of the loom. In addition to the constant breaking of the picker sticks, the lug strap is practically uncontrolled and is free to side lash and vibrate vertically, there being no means present to prevent or 30 absorb the shocks caused by the vertical movements of the lug strap, such movements being unnecessary for the proper action of the loom. It is true that a slight rocking motion of the lug strap during its operation 35 is necessary in view of the swing of the sweep stick and its operating connections. However, the old type of connection not only allows such necessary rocking movement, but also allows the above mentioned 40 vertical movement which causes injury to the parts and vibrations which if avoided would greatly benefit the loom.

One object of my invention is to provide 45 an improved lug strap connection and support for picker sticks which will remedy the above mentioned objectionable conditions and which will allow the employment of the well known construction of lug strap without alteration thereto or without alteration 50 or weakening of the picker stick. In other words, my invention can be used in connection with a regular laminated canvas lug strap and with an ordinary picker stick without in any manner changing or weakening 55 their constructions.

Another object is to provide a construction whereby an even application of the power in the plane and direction of movement of the lug strap can be obtained, at the same time allowing necessary swinging or 60 rocking of the lug strap, the construction being such as to prevent objectionable lateral deviation and the above mentioned unnecessary vertical motion of the lug strap. In this manner unnecessary vibration is reduced 65 to a minimum.

In addition to the above mentioned objects and advantageous features of my invention, the structure is such that the supporting means for the lug strap can be readily adjusted in the direction of the height 70 of the picker stick so as to adjust the power, said adjustment and construction being such that it will not weaken the picker stick.

These objects and other advantageous ends 75 which will be set forth hereinafter, I attain in the following manner, reference being had to the accompanying drawing in which—

Figure 1 is a fragmentary front elevation 80 illustrating my invention,

Figure 2 is an edge view of Figure 1,

Figure 3 is a sectional view taken on the line 3—3 of Figure 1, and

Figure 4 is a sectional view taken on the line 4—4 of Figure 1.

Referring to the drawing, 5 represents an ordinary picker stick and 6 represents a lug strap such as a laminated canvas lug strap having inclosed in its looped end a block 7 90 with an inner convex surface 8. The sweep stick is shown at 9, said sweep stick having an end portion secured between the legs 10 of the lug strap by a bolt 10^a. The extreme inner end of the sweep stick 9 is convex as 95 shown at 11 and is opposed to the convex surface 8 of the block 7 as clearly shown in Figures 1 and 3, the surfaces 8 and 11 being spaced apart to provide an opening 12 through which the picker stick 5 extends. 100 The opening 12 is of greater width than the picker stick so that the picker stick has its edge surfaces 13 and 14 respectively opposed to the surfaces 8 and 11.

An adjustable clamping band 15 surrounds 105 the picker stick and has a set screw 16 which engages a plate 17, said plate being operative to engage the edge surface 14 of the picker stick as shown in Figures 1 and 4. Thus by loosening and tightening the set 110

screw 16, the clamping band 15 can be secured to the picker stick at any position within the height thereof. The clamping band 15 has a laterally projecting pivot stud 18 which may either be cast integral with the band proper or otherwise firmly fixed thereto. This pivot stud has its axis at right angles to the wide side surface 19 of the picker stick and in a plane substantially midway between the edge surfaces 13 and 14 of the picker stick, as clearly shown in Figure 1 of the drawing.

A compensating and supporting link 20 has its upper end portion 21 pivotally supported on the stud 18, said link having a hole in its upper end through which the stud 18 projects. This link 20 is preferably made of greatly compressed fibre and may be retained in its position on the stud 18 by any suitable means. In the present instance I have illustrated a cotter pin 22 which extends through a hole in the stud 18 and I also preferably provide a fibre washer 23 between the cotter pin and the outer side surface 24 of the link 20.

The link 20 below the clamping band 15 is of greater thickness than at the top, the difference in thickness of the link being equal to the thickness of the band 15 so as to provide an inner or rear flat surface 25 which rests against the surface 19 of the picker stick 5. Furthermore, the link 20 is of such width that during the action of the sweep stick 9, the surface 25 will always be opposed to the surface 19. The link 20 has a slot 26 which extends entirely therethrough from its side edge 27 to its side edge 28 and through this slot extends the leg 29 of the lug strap 6, the slot being of such width that the leg 29 snugly fits therein but can slide and rock within the slot in a manner hereinafter rendered obvious. The upper end surface 30 of the slot 26 is convex and opposed to the lower convex end surface 31, the height of said slot 26 being slightly greater than the height of the lug strap, as clearly shown in Figures 1 and 2. It will also be observed that the lug strap embraces the picker stick and also embraces the portion 32 of the link 20 so that during the movement of the sweep stick 9, the link 20 will swing parallel with the side surface 19 of the picker stick and the convex surfaces 30 and 31 will allow a rocking movement of the lug strap without allowing the lug strap to jump or accidentally move vertically beyond the distance prescribed between the convex surfaces 30 and 31. Furthermore, the friction exerted between the lug strap, the picker stick and the link effects an initial movement to the picker stick on the reversal of the direction of movement of the sweep stick 9 so that the drastic or severe pounding noise is prevented and furthermore, the life of the picker stick is prolonged. This

action has been proved by long tests of the invention upon looms.

In addition to the above features, the arrangement of the link 20 with its surface 25 operative in conjunction with the surface 19 of the picker stick has been found to keep the lug strap and sweep stick in its proper plane of movement preventing lateral deviation and chattering of the parts.

Having thus described my invention what I claim as new and desire to secure by Letters Patent is:

1. The combination with a picker stick of means providing a lateral pivot; a link on said pivot and depending adjacent the side surface of said picker stick, said link having a slot therethrough; and a lug strap embracing said picker stick and having a leg portion extending through said slot.

2. The combination with a picker stick of means providing a lateral pivot; a link on said pivot and depending adjacent the side surface of said picker stick, said link having a slot therethrough; and a lug strap embracing said picker stick and having a leg portion extending through said slot, said link having a surface directly opposed to the side surface of the picker stick.

3. The combination with a picker stick of means providing a lateral pivot; a link on said pivot and depending adjacent the side surface of said picker stick, said link having a slot therethrough; and a lug strap embracing said picker stick and having a leg portion extending through said slot, the end surfaces of said slot being convex and opposed to each other.

4. The combination with a picker stick of means providing a lateral pivot; a link on said pivot and depending adjacent the side surface of said picker stick, said link having a slot therethrough; and a lug strap embracing said picker stick and having a leg portion extending through said slot, said link having a surface directly opposed to the side surface of the picker stick, the end surfaces of said slot being convex and opposed to each other.

5. The combination with a picker stick of a clamp adapted to be secured to the picker stick and having a laterally projecting pivot stud; a link pivotally depending from said pivot stud and opposed to the side surface of the picker stick; and a lug strap surrounding the picker stick and extending through said link.

6. The combination with a picker stick of a link pivotally supported adjacent a side surface of the picker stick and having a slot below its pivot, said slot extending through the link parallel with the side surface of the picker stick; and a lug strap embracing the picker stick and having a leg portion extending through said slot in the link, said link having a side surface di-

rectly opposed to said side surface of the picker stick, the opening through said lug strap being of such length as to keep said opposed surface of the link opposed to said side surface of the picker stick during the full extent of movement in either direction of the lug strap.

7. The combination with a picker stick of a clamping band on the picker stick; a link pivotally connected to said band at the outer side surface thereof, said link having a portion of increased thickness below said band substantially equal to the thickness of the side of said band whereby the lower portion

of the link is capable of directly engaging the side surface of the picker stick, said link having a slot therethrough; and a lug strap embracing said picker stick and having a leg portion extending through said slot.

In testimony whereof, I have signed my name to this specification, in the presence of two subscribing witnesses.

ELMER A. BARTON.
